UNITED STATES PATENT OFFICE.

ALFRED ROESCH, OF BROOKLYN, NEW YORK, ASSIGNOR TO CHARLES J. TAGLIABUE MANUFACTURING CO., OF BROOKLYN, NEW YORK, A CORPORATION OF NEW YORK.

HUMIDITY CONTROLLER.

Application filed April 29, 1920. Serial No. 377,609.

To all whom it may concern:

Be it known that I, ALFRED ROESCH, a citizen of the United States, and resident of the borough of Brooklyn, county of Kings, city and State of New York, have invented certain new and useful Improvements in Humidity Controllers, of which the following is a specification.

My invention relates to controllers whereby the percentage of humidity in the air of a room or the like is controlled and has for its object to provide an extremely sensitive device of simple construction for automatically controlling the difference between dry and wet bulb temperatures so as to automatically maintain a predetermined percentage of humidity, which may be either approximately constant or of progressive increase or decrease, in the atmosphere of a room or the like, and more particularly where large variations in temperature occur. My invention will be fully described hereinafter and the features of novelty will be pointed out in the appended claims.

In the accompanying drawings which, for illustrative and descriptive purposes and without intent to define the limits of the invention, show an example thereof and of its application, Figure 1 represents an installation of the invention; Fig. 2 is a plan view of the controller; Fig. 3 is a side view thereof; Fig. 4 is a detail section on the line 4—4 of Fig. 5, and Fig. 5 is a similar view on the line 5—5 of Fig. 3.

As shown more particularly in Figs. 2, 3 and 4, the controller comprises a base 5 of any suitable construction upon which a capsular spring 6 of customary type is mounted and connected by means of a capillary tube 7 with a sensitive member in the form of a bulb 8. A main lever 9 is fulcrumed at 10 upon uprights 11 which project from the base 5 and is provided with an adjustable projection preferably in the form of a screw 12 which is maintained in contact with the capsular spring 6 by means of a spring 13 located between and engaging one end of said lever 9 and the base 5. The main lever 9 carries a capsular spring 14 also of any well known type and connected through the medium of the capillary tube 15 with a sensitive member which may also

be in the form of a bulb 16. A secondary lever 17 is pivoted at 18 upon uprights 19 extending from the main lever 9, said lever 17 being provided with an adjusting screw 20 which bears against the capsular spring 14 and is maintained in contact therewith by a spring 21 located between the two levers 9 and 17. In the preferred arrangement the screw 20 carries a pointer 22 which co-operates with a suitable scale 23 provided upon the lever 17 to visibly indicate the adjustment to which the screw 20 is set.

The base 5 carries a block 24 which is provided with channels 25 and 26 connected by means of pipes 27 and 28 with a source of air or other fluid under pressure and with a diaphragm motor valve 29 constructed and arranged to close when pressure is applied to the diaphragm and to open under the action of a spring 29^a when the pressure upon said diaphragm is relieved. A valve casing 30 is attached to the block 24 and is provided with an inlet passage 31 communicating with the channel 25 and thus with the supply of fluid under pressure and has an outlet passage 32 communicating with the channel 26 and thus with the diaphragm motor valve 29. Both passages 31 and 32 are also in connection with a chamber 33 in which a valve 34 of the ball type is located, the passage 31 being formed with a seat for the accommodation of said valve 34. The latter is arranged to also control an exhaust passage 35 which establishes communication between said chamber 33 and the atmosphere; a stem 36 extends through and beyond said exhaust passage 35 and at its inner end engages the ball valve 34 while its outer end is adapted for engagement by a lug 37 located on the secondary lever 17. The diameter of the stem 36 is such that a space exists between it and the passage 35 which space constitutes the actual exhaust passage previously referred to.

In the example of installation chosen for illustrative purposes and shown in Fig. 1, 38 represents a room in which the temperature throughout a given period may vary, for instance, from 60° to 110° F., especially in the summer time, and in which it is important that the percentage of humidity remain constant regardless of any changes in

the dry bulb temperature. The room 38 is provided with an air duct 39 and with ventilating ducts 40 and 41 in all of which dampers or equivalent devices 42 are located 5 for manually regulating the ventilation.

The controller itself, preferably enclosed in a casing 5^a may be placed in any convenient position preferably outside of the room 38 and is connected by the capillary tubes 7 and 15 respectively with the dry bulb 8 and the wet bulb 16, both of which are located within the room 38 at points where the average temperature prevails. It will be understood that the capsular spring 6, capillary tube 7 and bulb 8 and likewise the capsular spring 14, capillary tube 15 and bulb 16 are partly or wholly filled with a volatile fluid which will cause the capsular springs 6 and 14 to expand when the bulbs 8 and 16 are subjected to an increase in temperature and to contract when said bulbs are subjected to a decrease in temperature. The wet bulb 16 is provided in the customary manner with a wick 43 depending into a water tank 44 to which water is supplied through a suitable pipe 45 and in which an overflow 46 is located to conduct any surplus supply of water from said tank.

The pipe 27 leads from the controller to 30 a source of air under pressure while the pipe 28 leads to the diaphragm motor valve 29, which in the illustrated example controls a water supply pipe 47 which terminates, within the room 38, in a spray nozzle 48 preferably located within an open ended tube 49 as shown. The spray issuing from the nozzle 48 humidifies the air surrounding it and causes a downward movement of said air whereby a circulation is created in the room 40 38, by way of the air inlet duct 39 and the ventilating ducts 40 and 41 which may be manually regulated by means of the dampers 42.

By way of example let it be assumed that, 45 as before stated, the dry bulb temperature may vary from 60° to 110° F. during a given period of time and that 48% of humidity is desired to be maintained in the room 38 throughout said period. According to the 50 psychrometric tables issued by the Bureau of Standards, a dry bulb or air temperature of 60° F. and a ten degrees depression of the wet bulb equals 48% of humidity, while with a dry bulb or air temperature of 110° 55 F. a nineteen degrees depression of the wet bulb equals 48% of humidity. In order to maintain approximately a 48% of humidity at all stages during the change in the dry bulb temperature from 60° to 110° F., it is 60 therefore necessary to provide for a gradual increase in the difference between the dry and wet bulb temperatures. If this is not done and the difference between said dry and wet bulb temperatures is permitted to 65 remain substantially constant at ten degrees,

the humidity will reach 70% at a dry bulb temperature of 110° F. according to said psychrometric tables.

In the illustrated example the desired result, that is, the maintenance of the humidity 70 at approximately 48%, is secured as follows: The controller is adjusted for a dry bulb temperature of 60° and a wet bulb temperature of 50° by properly setting the screw 20 and its pointer 22 with respect to the scale 75 23. With this adjustment and assuming that the dry bulb temperature is at 60° F. and the wet bulb temperature is at 50° F. to maintain the 48% of humidity, the lug 37 of the secondary lever 17 is in contact with but 80 exerts practically no pressure on the valve stem 36. At this stage the ball valve 34 is maintained in a position by the air pressure to close the exhaust passage 35 and thus permit the air pressure to reach the dia- 85 phragm valve 29, which is thus in its closed position.

If now the dry bulb temperature rises the corresponding expansion of the fluid in said dry bulb 8 will create a higher pressure in 90 the capsular spring 6 thereby expanding the same and pivotally raising the main lever 9 and compressing the spring 13. This pivotal movement of the main lever 9 is partaken of by the secondary lever 17 with the result that 95 the lug 37 exerts a push upon the stem 36 whereby the latter is moved inward and the ball valve 34 is forced away from the inner end of the exhaust passage 35 and toward the inner end of the air passage 31. 100 The supply of air under pressure is thus wholly or partly cut off from the valve 29 which as a result is opened by the action of its spring 29^a and thus causes a spray to issue from the nozzle 48. This brings about 105 an increase of humidity in the air of the room 38 and raises the wet bulb temperature which creates a higher pressure in the capsular spring 14 and thereby expands the same.

This expansion is communicated to 110 the screw 20 and pivotally moves the secondary lever 17 to compress the spring 21 and to lift the lug 37 away from the end of the stem 36; it will be understood that the action of the capsular spring 14 and the 115 movement of the secondary lever 17 are relative to the main lever 9. As the lug 37 is raised and thus relieves the stem 36 from restraint, the air pressure will cause the ball valve 34 to close the exhaust passage 35 120 and to establish communication between the channels 31 and 32 by way of the chamber 33. The pressure will thus act upon the dia- 125 phragm of the valve 29 and cause the same to close thereby shutting off the supply of water to the nozzle 48. A reduction of the dry or wet bulb temperature will have an opposite effect upon the humidity valve 29.

This alternate operation of the main and secondary levers through the expansion or 130

contraction of the capsular springs 6 and 14 is repeated throughout the given period of time during which the percentage of humidity in the air is to be maintained.

5 In the illustrated example the multiplication of the movement of the secondary lever 17, with relation to the movement of the main lever 9, is somewhat less and as the temperature increases and the capsular 10 springs 6 and 14 expand at the same ratio, following each other, the differences between the dry and wet bulb temperatures will therefore be gradually increased, until it is 19° F. at a dry bulb temperature of 110° 15 F. The humidity of 48 per cent is thus maintained, within a very slight variation, throughout the rise from 60° to 110° F. It will be understood that the apparatus 20 may be set for other combinations with equal facility and that the same efficient results will in each case be automatically obtained.

The device may readily be modified to also automatically control any gradual increase or decrease of the percentage of humidity desired in a given period of time and in relation to any increase or decrease in the dry bulb temperature. This may be done by changing the relative location of 25 the fulcrums of the operating levers so that the difference in the temperatures of the dry and wet bulbs will be increased or decreased as the room temperature rises or falls. The same results may be accomplished by using a fluid in one of the bulbs which has a greater expansibility or creates a greater pressure for each degree increase in the dry bulb temperature, than the fluid in the other bulb.

40 My invention is simple in construction and efficient in operation and once it is set requires no attention as its operation is entirely automatic and in accordance with predetermined desires.

45 Various changes in the form shown and described may be made within the scope of the claims without departing from the spirit of my invention.

I claim:

50 1. The combination of air-humidifying means, a dry bulb, a wet bulb, expandible

and contractible devices connected respectively with said bulbs and capable of independent operative expansive and contractive movements in the same directions, and 55 means operated alternately by said devices to automatically control the humidifying means in accordance with the differences between the dry bulb and wet bulb temperatures to provide predetermined percentages 60 of humidity in said air.

2. The combination of air-humidifying means, a diaphragm motor valve controlling the same, an air controlling valve whereby air under pressure is admitted to and cut 65 off from said diaphragm valve, a pivoted main lever, a secondary lever pivotally mounted on said main lever, a capsular spring, a dry bulb connected therewith whereby said capsular spring is caused to 70 operate both levers and thereby actuate said air controlling valve to cut off the air pressure from said diaphragm motor valve to permit same to open, a second capsular 75 spring carried by said main lever and having operative movements in the same direction as said first capsular spring, a wet bulb connected with said second capsular spring and whereby the latter is caused to actuate said secondary lever relatively to the main 80 lever and thereby actuate said air controlling valve to admit air pressure to said diaphragm motor valve to close the same.

3. The combination of air-humidifying means, a diaphragm valve controlling the 85 same, an air controlling valve whereby air under pressure is admitted to and cut off from said diaphragm valve, a pivoted main lever, a secondary lever pivotally mounted on said main lever, a dry bulb, a wet bulb, 90 and means connected with said bulbs and having operative movements whereby said levers are coincidentally operated and whereby said secondary lever is independently operated to actuate said air controlling valve to alternately cut off and admit air pressure to said diaphragm motor valve and thereby alternately open and close the latter.

In testimony whereof I have hereunto set 100 my hand.

ALFRED ROESCH.
